UNITED STATES PATENT OFFICE.

PATRICK A. MARTIN, OF BIRMINGHAM, ENGLAND.

DESIGN FOR A GOLF-BALL.

59,366.

Specification for Design.

Patented Oct. 11, 1921.

Application filed October 12, 1920. Serial No. 416,557. Term of patent 7 years.

To all whom it may concern:

Be it known that I, PATRICK ALPHONSUS MARTIN, subject of the King of Great Britain, residing at Birmingham, England, have invented a new, original, and ornamental Design for Golf-Balls, of which the following is a specification, reference being had to the accompanying drawing, forming part thereof.

Figure 1 is a plan view of the golf ball.

Fig. 2 is an elevation of same.

Fig. 3 is a sectional view taken through the center of the ball.

Fig. 4 is a fragmentary view of the outer casing of the ball to an enlarged scale.

Fig. 5 is a transverse sectional view of Fig. 4.

What I claim as new and desire to secure by Letters Patent is:—

The ornamental design for a golf ball, as shown.

In testimony whereof I have hereunto set my hand in presence of two subscribing witnesses.

P. A. MARTIN.
